CLAIM

The ornamental design for a network connectivity tester, as
shown and described.

(21) Appl. No.: **29/153,645**

DESCRIPTION

(22) Filed: **Jan. 9, 2002**

FIG. 1 is a perspective view of a network connectivity tester
showing my new design;

(51) LOC (7) Cl. **10-04**

FIG. 2 is a front plan view thereof;

(52) U.S. Cl. **D10/78**

FIG. 3 is a right side elevation view thereof;

(58) Field of Search D10/78; 324/66,

324/67, 158 F, 539-542; 379/1-10, 21,

60, 66, 96, 105-107; 340/321, 540, 565,
566, 571-573

60, 66, 96, 105-107; 340/321, 540, 565,

566, 571-573

(56) **References Cited**

FIG. 4 is a rear plan view thereof;
FIG. 5 is a left side elevation view thereof;
FIG. 6 is a top elevation view thereof; and,
FIG. 7 is a bottom elevation view thereof.
